UNITED STATES PATENT OFFICE.

HENRY E. JACOBS, OF FOND DU LAC, WISCONSIN.

ELECTRIC TEMPERATURE-CONTROLLING DEVICE.

SPECIFICATION forming part of Letters Patent No. 363,645, dated May 24, 1887.

Application filed September 27, 1886. Serial No. 214,594. (No model.)

To all whom it may concern:

Be it known that I, HENRY E. JACOBS, a citizen of the United States, residing at Fond du Lac, in the county of Fond du Lac and State 5 of Wisconsin, have invented a certain new and useful Improvement in Electric Temperature-Controlling Devices; and I hereby declare the following to be a full, clear, and exact description of the same.

10 My improvement relates to the class of electrical apparatus used for automatically controlling the temperature of apartments or inclosures, whether by ventilation or by heat regulation, and comprising, broadly, an electrical apparatus the circuit containing which is opened and closed by the action of a thermostat or other suitable heat-measuring instrument to admit or shut off the power—usually compressed air—employed to actuate 15 the valve, damper, or ventilator in the passage through which the temperature-affecting medium enters the apartment or inclosure the temperature of which is to be controlled or regulated. As stated, the power commonly 20 employed to actuate such valve, damper, or ventilator, for the purpose set forth, is compressed air, which ordinarily necessitates the provision of a storage-tank to contain it and a pump to supply the storage-tank—items 25 which add materially to the initial cost of the apparatus, and which, particularly the pump, incur expense and trouble in their maintenance, owing to repairs rendered necessary by wear.

30 It is my object to provide an apparatus wherein these difficulties shall be overcome by avoiding the use of compressed air or other power requiring special generating and storage appurtenances and providing a mechanism 35 of comparatively simple construction, but effective in its purpose, operated by hydraulic power, whereby in places provided with water-power introduced into the houses the device may be connected with a hydrant.

40 In the drawings, Figure 1 is a partly sectional and broken diagrammatic view of my improved apparatus; Fig. 2, a sectional view of a detail; Fig. 3, a side elevation of a detail, showing a modification; Fig. 4, another detail 45 in end elevation; Fig. 5, a sectional view of still another detail, and Fig. 6 a sectional plan view taken on the line 6 6 of Fig. 5.

A is a box containing, with the exception of the battery B, thermostat C, and contact-points r and r' , hereinafter more particularly 55 referred to, the entire electrical apparatus portion of my device.

D and D' are electro-magnets supported with- 60 in the box A at right angles to each other, the latter having an armature, E, in the form of a bar provided with a notch, q , secured at one end to hang within the box to a reciprocating rod, q' , supported to extend above the magnet D longitudinally of the same, and pro- 65 vided toward one end with stops p and p' and a spiral spring, o , confined between the stop p and side of the box, or a stop, p' , as shown, and having a tendency to force the rod in a direction to remove the armature E from contact with the magnet D'. The magnet D has 70 an armature, F, on the lever F', of non-con- 75 ducting material, pivotally supported, as shown, to extend across the magnet, and pro- vided at one extremity with a catch, n , to en- gage with the armature E in the manner and 80 for the purpose hereinafter described. The opposite end of the lever F' embraces the stem G of a valve device, G, hereinafter described, 85 which stem extends into the box A, and is sur- rounded by a spiral spring, o' , confined be- 90 tween a stop, t , forming a guide for the stem, and an adjustable stop, t' , by means of which the tension of the spring is regulated, its tendency being, like that of the spring o , to maintain the armature F away from the elec- 95 tro-magnet D. Contact-points p^2 and p^3 are con- 100 nected by conductors x^2 and x^3 with the contact- points r and r' external to the box A, and be- 105 tween which extends the thermostat C, con- nected, as shown, with one pole of the bat- tery B, the opposite pole of which is con- 110 nected, as shown, to the magnets D and D'.

H is a circuit opener and closer, comprising a bar, m , of insulating material, pivotally supported at one end in the box to cause its 95 opposite end to extend between the stops p and p' on the shifting rod q' and between the contact-points p^2 and p^3 , and provided with lateral metal prongs l and l' , connected, respectively, by conductors x and x' with the magnets D 100 and D'.

I is a pipe to be connected at its open ex- tremity with the hydraulic power, which, if obtained from a hydrant, may be led to the

device by coupling the pipe I to a faucet. The pipe I leads into a chamber, K, at its base, which is covered by an air and water tight flexible diaphragm, K', and between the source 5 of water-power and the chamber K is a valve device, L, (shown in detail in Fig. 2,) and also the valve device G, already referred to, and shown in detail in Figs. 5 and 6.

Leading from the upper side of the chamber K is a pipe, I', which communicates at its opposite extremity with a chamber, M', formed in a bowl, M, by means of a flexible diaphragm, M', upon the center of which is secured a bearing, k, preferably in the form of parallel vertical arms, as shown in Fig. 4, between which to pivot a lever, N, at its rear extremity, fulcrumed toward its center in a similar bearing, k', on the bowl M.

Intermediately between the device M and chamber K in the pipe I' is a coupling, I², at which is connected a vertical branch pipe, I³, leading to the valve device L, which comprises a shell, i, provided at its upper end with a chamber, K², into which the pipe I³ enters at 25 the top, and closed at its base from communication with the shell by means of a flexible diaphragm, K³, like the diaphragm K', and carrying a valve-stem, i', provided at its lower end with a valve, i², which serves to open and 30 close communication between the passages i³ and i², provided in the pipe I, by means of a joint, i⁵, to which the shell i is connected. The purpose of the valve i² is to act as a governor, whereby the apparatus may be relieved of the 35 effect of the hydraulic pressure when the latter is not required, as will more clearly appear hereinafter.

The valve device G also comprises a shell, h, opening at its upper end into the box A, 40 but separated therefrom by a flexible water-tight diaphragm, K⁴, through which passes the valve-stem G', carrying at its lower end a valve, G², of the form shown in Fig. 6, inclosed within a chamber or shell, h', in the shell h, 45 and which shell h' is open around the valve-stem. A joint, h², is connected into the pipe I, to receive the valve device G, and contains separated passages g and g', each bent from its longitudinal course to extend vertically, as 50 shown, in the joint h², the vertical part of the passage g, however, extending higher than that of the passage g', to enable it to be closed by lowering the valve G² upon its seat, while the passage g' can never be so closed.

55 With the foregoing description of the parts of my apparatus its operation will be readily understood from the following: On connecting the pipe with the water-power—hydrant-faucet—and the lever N with the damper of the furnace or valve in a hot or cold air or hot-water passage, the device is ready for operation. It will be understood that the thermostat and contact-points r and r' are necessarily located in the apartment or inclosure 60 the temperature of which is to be regulated, while the other parts of the apparatus may occupy convenient position in any suitable lo-

cation and arrangement. With the thermostat in contact, as shown, with the contact-point r—a position it has been caused to assume, say, 70 by a rise of temperature in the apartment beyond what is required—the circuit containing the magnet D will be closed, causing attraction of the armature F and consequent release of the armature E, locked against the magnet 75 D', with the armature F in its raised position, by the catch n, which, on being released by the action of the spring o upon the shifting rod q', breaks the circuit by moving the circuit-breaker H into contact with the contact-point 80 p³, where it is ready to continue the circuit containing the magnet D' when the thermostat shall make contact at the contact-point r' with a fall of the temperature of the apartment below the desired degree. It will thus be seen 85 that immediately after either magnet is electrified the circuit is broken, to save the battery, but that the armature of such magnet is locked to the same to maintain the parts of the apparatus which it controls in desired op- 90 erative condition until the other magnet shall be electrified. Thus, when the armature F is attracted, the lever F' releases the armature E, which it had previously locked, and in turn is locked by the armature E, owing to the en- 95 gagement of the latch n with the notch q, and when the latter is attracted, releasing the notch and latch from each other, the spring o' will raise the locking end of the lever F', causing it to hold the armature E against the magnet D'. 100 Attraction of the armature F raises the valve G², thereby closing the passage in the shell h' around the valve-stem G' and opening communication between the passages g and g', whereby 105 water is permitted to pass through the pipe I (raising the valve i² by the force of its pressure) into the chamber K below the diaphragm K'. The chambers K, K², and M' and pipe I' contain air at normal pressure, which is compressed by the force of water-pressure exerted 110 against the diaphragm K', thereby forcing the diaphragm K³ downward and closing the valve i² by pressing it against its seat to reduce the pressure, and forcing the diaphragm M' upward, whereby the oscillating end of the lever 115 N is moved downward from its normal position, as shown, to adjust the damper or valve with which it is connected, as aforesaid, in the desired manner. The movement of the lever 120 N from its normal position by the pressure 125 underneath the diaphragm M' may be the reverse of that described by pivoting it at its end in the bearing k², instead of in the bearing k. The apparatus remains in this condition, owing to the locking of the armature F against the 130 magnet D, until the change of temperature in the apartment or inclosure shall produce contact of the thermostat with the point r', when the consequent release of the lever F' and armature F will lower the valve G² against the 135 passage g and from the opening around the valve-stem G', permitting the water in the pipe I, between the passage g and chamber K, to discharge through the valve G² into the

shell h , and from the apparatus through a waste-pipe, f , thereby permitting the diaphragms K' and M' to resume their normal positions, causing the valve or damper controlled by the lever N to be moved in the opposite direction for the desired purpose, and again permitting the pressure of the water-power to overcome the resistance of the diaphragm K' and raise the valve i . Of course, when the thermostat is again caused to make contact at the point r the operation of the apparatus will be that first described.

What I claim as new, and desire to secure by Letters Patent, is—

1. The combination of a valve-controlling electrical apparatus in a circuit opened and closed by the automatic action of a heat-measuring instrument, a valve-controlling lever, N , a close compressible air-passage with one end 15 of which the lever N is connected and containing air at normal pressure, and a water-passage connected with the opposite end of the air-passage through which to introduce hydraulic pressure against the air-passage to 20 compress it and thereby actuate the lever N , substantially as and for the purpose set forth.
2. The combination of a valve-controlling self-locking electrical apparatus in a circuit opened and closed by the automatic action of 25 a heat-measuring instrument, a valve-controlling lever, N , a close compressible air-passage with one end of which the lever N is connected and containing air at normal pressure, and a water-passage connected with the 30 opposite end of the air-passage through which to introduce hydraulic pressure against the air-passage to compress it and thereby actuate the lever N , substantially as and for the purpose set forth.
3. The combination of a valve-controlling self-locking electrical apparatus in a circuit 35 opened and closed by the automatic action of a heat-measuring instrument and provided with a circuit opener and closer, H , a valve-controlling lever, N , a close compressible air-passage with one end of which the lever N is 40 connected and containing air at normal pressure, and a water-passage connected with the opposite end of the air-passage through which to introduce hydraulic pressure against the air-passage to 45 compress it and thereby actuate the lever N , substantially as and for the purpose set forth.
4. The combination of a valve-controlling lever, N , a close compressible air-passage with 50 one end of which the lever N is connected and containing air at normal pressure, a water-passage connected with the opposite end of the air-passage through which to introduce 55 hydraulic pressure against the air-passage to compress it and thereby actuate the lever N , and an electrical apparatus for controlling the valves in the water-passage in a circuit opened and closed by the automatic action of a heat-measuring instrument, and comprising electro-magnets D and D' , having their armatures

maintained normally out of contact with them and mutually interlocking, substantially as and for the purpose set forth.

5. The combination of a valve-controlling lever, N , a close compressible air-passage with one end of which the lever N is connected and containing air at normal pressure, a water-passage connected with the opposite end of the air-passage through which to introduce 75 hydraulic pressure against the air-passage to compress it and thereby actuate the lever N , and an electrical apparatus for controlling valves in the water-passage in a circuit opened and closed by the automatic action 80 of a heat-measuring instrument, and comprising electro-magnets D and D' , having their armatures maintained normally out of contact with them and mutually interlocking, and an automatic circuit opener and closer, 85 H , substantially as and for the purpose set forth.

6. The combination of a valve-controlling lever, N , a close compressible air-passage with one end of which the lever N is connected 90 and containing air at normal pressure, a water-passage connected with the opposite end of the air-passage through which to introduce hydraulic pressure against the air-passage to compress it and thereby actuate the 95 lever N , and an electrical apparatus for controlling valves in the water-passage in a circuit opened and closed by the automatic action of a heat-measuring instrument, and comprising an electro-magnet, D , having its armature F on a pivoted lever, F' , maintaining the armature normally out of contact with its magnet, and provided with a catch, n , an electro-magnet, D' , having an armature, E , provided with a notch, g , and connected with a shifting 100 spring-rod, q' , which maintains it normally out of contact with its magnet, contact-points p^2 and p^3 , and a circuit opener and closer, H , connected with the bar q' , to be actuated by its shifting movements, substantially as and 105 for the purpose set forth.

7. The combination of a valve-controlling electrical apparatus in a circuit opened and closed by the automatic action of a heat-measuring instrument, a valve-controlling lever, N , a chamber, K , having a diaphragm, K' , a compressible chamber, M' , supporting the lever N , a pipe, I' , connecting the chambers K and M' , a pipe, I , leading to the diaphragm K' , a valve device, L , in the pipe I , 115 surrounded by and connected with a compressible chamber, K^2 , communicating with the pipe I' , and a valve device, G , having disconnected passages g^2 and g^3 in the pipe I , and a discharge, f , and having its stem G' connected with the lever F' of the electrical apparatus, the whole 120 being constructed and arranged to operate substantially as and for the purpose set forth.

HENRY E. JACOBS.
